UNITED STATES PATENT OFFICE.

ALBERT DAIGNAULT, OF ST. MATHIAS, QUEBEC, CANADA, ASSIGNOR TO ELZÉAR DORÉ,
OF LAPRAIRIE, QUEBEC, CANADA.

BLOWER.

Application filed November 20, 1919. Serial No. 339,351.

To all whom it may concern:

Be it known that I, ALBERT DAIGNAULT, a subject of the King of Great Britain, residing at St. Mathias, Province of Quebec, 5 Canada, have invented certain new and useful Improvements in Blowers; and I do hereby declare that the following is a full, clear, and exact description of the invention, such as will enable others skilled in the art to 10 which it appertains to make and use the same.

The present invention relates to a blower or elevator for lifting straw or the like, whereby the straw may be elevated so as to 15 be placed upon stacks or blown within the loft of the barn.

An object of the present invention is to provide a strong, durable and efficient device of this character which may be easily and 20 readily transported from place to place and one which will be comparatively inexpensive in the cost of manufacture.

With the above and other objects in view which will hereinafter appear as the description continues, the invention consists of 25 the novel features of construction, combination and formation of parts as will be hereinafter more fully described and particularly pointed out in the appended claim.

30 In the accompanying drawings has been shown a simple and preferred form of the invention, it being, however, understood that no limitation is necessarily made to the precise structural details herein exhibited, but 35 the right is hereby reserved to any changes, alterations or modifications to which recourse may be had that come within the scope of the claim without departing from the spirit of the invention or sacrificing the 40 efficiency of the same.

In the accompanying drawings:

Figure 1 is a side elevation of the apparatus embodying the present invention;

Figure 2 is a vertical longitudinal section 45 through the same;

Figure 3 is an end elevation; and,

Figure 4 is a detail section of the fan.

Referring now more particularly to the accompanying drawings wherein like and 50 corresponding parts are designated by similar reference characters throughout the several views.

The numeral 1 indicates a portable hous-

ing or casing which comprises a pair of spaced end plates 2, a rear wall 3 and a front 55 wall 4. Supported within these walls of the housing is a cylindrical casing 5 having an outlet 6 which is in communication with a spout 7. Journaled within the bearings 8 carried by the walls 2 is a shaft 9 and this 60 shaft carries a pair of spaced hubs 10 having formed integral therewith the radially extending spokes 11 each having a longitudinal slot formed at the outer end and in which slots are disposed the blades 12 of the 65 fan. The side walls 2 of the housing are provided with the air inlet openings 13 which lead into the casing 5. The front wall 4 and the casing 5 are provided with aligned inlet openings in which is adapted to rest 70 one end of an endless conveyor 14 and the opposite end of this endless conveyor is supported so that the conveyor will rest on an incline by means of the bars 15. Connected to the shaft 9 is a pulley 16 whereby the 75 shaft 9 may be rotated through a suitable source of power and upon the rotation of this shaft the fan will set up a suction within the casing 5, whereby the straw delivered to the fan casing will be blown or elevated 80 through the spout 7.

From the foregoing it is obvious that this device may be transported from place to place and that when straw is drawn upon the conveyor 14, this conveyor will deliver 85 the straw into the casing 5 and when the fan within this casing 5 is set up in motion it will elevate the straw through the spout 7 whereby the straw will be blown upon a stack or may be elevated within a loft or a 90 barn or other suitable building.

Having thus fully described my invention, what I claim as new and desire to secure by Letters Patent is:

The combination with an inclined endless 95 conveyor, of a blower including a housing comprising a pair of end walls, a front and rear wall connecting the edges of said end walls, a cylindrical casing supported within said walls, said casing having inlet and outlet openings arranged in its lower and upper portions respectively, air inlet openings arranged in said end walls concentrically of said cylindrical casing, bearings secured to said end walls exteriorly thereof, a shaft 100 journaled in said bearings, a fan carried by

said shaft and rotatable in the direction of the conveyor, and a pair of bars secured to said end walls and said conveyer for supporting the latter in an inclined position, the 5 lower end of said conveyer being disposed within said inlet opening and adapted to deliver the grain within said casing whereby said grain is carried through the inlet by the

the action of said fan, substantially as and in the manner described. 10

In witness whereof I have hereunto set my hand.

ALBERT DAIGNAULT.

Witnesses:

LOUIS BLAIN,
U. DUCLOS.
